LOUIS FRANK, OF FLUSHING, NEW YORK, ASSIGNOR TO GREENPOINT METALLIC BED CO., INC., OF BROOKLYN, NEW YORK, A CORPORATION OF NEW YORK.

TUBE-BENDING MACHINE.

Application filed June 3, 1926. Serial No. 113,365.

This invention relates to metal tube or pipe bending machines of the type wherein a tube or pipe may be bent to a desired shape without deforming its cross-sectional configuration, and without injury to its molecular structure.

The invention contemplates a machine wherein a pair of forming members are mounted in opposed relationship for engaging opposite sides of the pipe or tube to be bent, one of said forming members having a profile corresponding to the desired bend, and preferably having mounted with it a tube clamping vise. The profile forming member and the vise are movable preferably by oscillation about a fixed axis, and the other forming member while firmly maintained against the tube, may preferably be free to float or move in a path substantially tangent to the travel of the profiled edge of the first forming member. When the bend to be produced is a compound, eccentric or otherwise irregular curve, one of the forming members is preferably moved laterally with respect to the other to compensate for such irregularity, and for this purpose a suitable cam may be employed for synchronous operation with the profiled forming member. To facilitate insertion and removal of the work the preferably free or floating forming member may be withdrawn from its position in opposition to the other forming member, and furthermore, to increase the usefulness of the machine, the work clamping device is preferably provided with a plurality of sets of jaws for accommodating the work in different stages. The tube being operated upon may be protected from crumbling by suitable means such as a flexible mandrel inserted within the tube, and may be further restrained from outward bulging by confining it in a groove in the profiled forming member, the bottom of the groove having the desired curved profile and the side walls of the groove being formed by flanges, one of which may preferably be movable away from the other for releasing the tube after the bending operation is completed. Various adjustments are provided whereby the machine is capable of operating on different sizes of tub-

ing and the whole assemblage is such as to constitute a substantial advance in the art.

An important object of the invention is to provide a machine for accurately bending thin walled metal tubing to a desired shape without injury to the walls of the tubing; and a more special object is to provide such a machine for the production of eccentric, compound or otherwise irregular curves in tubing such as used in making the ends of the head and foot pieces of metallic bedsteads, which have two such bends connecting the posts or uprights with the transverse or horizontal portion.

Other objects are to provide a machine which is adapted to efficiently and in a simple manner produce a smooth bend in metal tubing, the machine being of such a nature that more or less unskilled labor may control and operate it, and to provide such a machine capable of operating on different sizes of tubing as desired.

These being among the objects of the present invention, the same consists of certain features of construction and combinations of parts to be hereinafter described and then claimed with reference to the accompanying drawings illustrating a preferred embodiment of the invention, and in which:

Fig. 1 is a plan of the improved bending machine showing a straight metal tubing in position to be clamped preliminary to forming the first bend;

Fig. 2 is a plan of the machine showing the tubing, after it has received its first bend, placed in the machine and clamped in position ready to produce the second bend;

Fig. 3 is a plan of the machine in which the tube carrier has been rotated to a predetermined degree to produce the second bend in the tubing;

Fig. 4 is a vertical central section of the machine showing the tubing clamped therein;

Fig. 5 is a section on the line 5—5 Fig. 1;

Fig. 6 is a horizontal section on the line 6—6 Fig. 4;

Fig. 7 is a section on the line 7—7 Fig. 1 showing a vise rigged up to clamp the tubing preliminary to the first bend;

Fig. 8 is a transverse section on the line 8—8 100

Fig. 3 showing the vise as it is rigged up to clamp the tubing at its first bend while producing the second bend;

Fig. 9 is a sectional plan of the forming head of the tube carrier, partly broken away and partly in section;

Figs. 10 and 11 are perspective views, respectively, of the clamping members adapted to fit the vise for clamping a straight length 10 of tubing;

Figs. 12 and 13 are perspective views, respectively, of clamping members adapted to fit the vise for clamping the tube at a portion which has already been bent;

Fig. 14 is a detail transverse section on the line 14—14 Fig. 1 showing the table or platform of the machine and the carriage portion associated with the control cam;

Fig. 15 is a broken detail transverse section 20 on the line 15—15 Fig. 9; and

Fig. 16 is a detail sectional view showing a flexible mandrel within the tubing preliminary to bending.

Referring to Figs. 1, 4, 5 and 6 of the drawings in particular, the machine is driven by a shaft 10 on which is fixed a double friction cone 11 in a well known manner so as to permit the cone to be moved lengthwise and yet be rotated by the shaft 10. Cone pulleys 12, 30 13 are mounted loosely on the drive-shaft 10, so that the double friction cone 11 is located between them. A flat belt 14 is trained on pulley 12 for forward driving movement of the machine, and a similar belt 15 is trained 35 on pulley 13 and crossed for a reverse driving movement. Bearing blocks 16, 16^a are provided and therein the shaft 10 is journalled.

As more particularly shown in Figs. 4, 5 and 6, the main portion of the machine is provided with a base 17 which carries uprights or 40 frame sections 18, 19, 20 bolted or otherwise rigidly secured to the base 17. Said uprights support a table top or platform 21 which may be of any preferred shape most suitable for 45 the work to be performed. A vertical spindle 22 is journalled in a step bearing 23 at the base of the machine and its upper portion is received in a bearing 24 at the table top or platform 21. A large speed reducing gear-50 wheel 25 is rigidly keyed or otherwise permanently secured to the spindle 22.

In order to slowly turn the gear-wheel 25 from either one of the belt pulleys on the drive-shaft 10, suitable speed reducing mechanism is provided. The pulleys 12, 13 are 55 shown as mounted at that end of the shaft 10 which is outside the frame proper of the machine, and the other end of the shaft 10 is provided with a bevel-pinion 26 rigidly secured thereto. This pinion 26 is in constant mesh with a bevel-gear 27 which is rigidly secured to a shaft 28 journalled in a bearing block 29 and in the upright 20 of the frame. Shaft 28 extends at right-angles to the drive-60 shaft 10 and is provided at its outer end with

a pinion 30 which is in constant mesh with a gear-wheel 31 rigidly secured to a counter-shaft 32 also journalled in the frame upright 20.

The inner end of the counter-shaft 32 is 70 provided with a bevel-pinion 33 which is in constant mesh with a bevel-gear 34 adapted to turn on the shaft 35 mounted rigidly on the base and table top of the frame of the machine. Bevel-gear 34 may be suitably constructed to rest upon a collar 34^a rigidly secured to the upright shaft 35. The bevel-gear 34 is provided with a hub extension in the form of a sleeve 36, which is formed with a power applying gear 38, the teeth of which 80 are in constant mesh with the teeth of the large slow-speed gear-wheel 25. Briefly the drive-shaft 10 when driven by either of the belt pulleys 12, 13 will transmit motion at reduced speed and increased power to the 85 large gear-wheel 25, the pinion 26 driving the gear 27, the pinion 30 the gear 31, the pinion 33 the gear 34 and the pinion 38 the large gear 25, all being driven as parts of said train in the order enumerated. The operation of 90 the described driving mechanism will be detailed more particularly hereinafter.

With more particular reference to Figs. 1, 2 and 3, the tube carrier and concomitant parts will now be described. The forming head 39 of the tube carrier is keyed to the upper end of the spindle 22, so that it may be oscillated or swung within predetermined limits in a horizontal plane just above the table 21. The forming head 39 may be constructed in any preferred manner so as to provide a tube receiving recess 40 on the forming portion of the head and away from the axis of the carrier spindle 22, the recess being so constructed that the bottom thereof, as indicated in dotted lines, conforms to the desired bend to be produced in the tubing. In the embodiment of the invention as shown 100 the length of the recess and its curvature are such that two eccentric bends may be made in metallic tubing as, for instance, for bed ends of pieces. In Fig. 1 that portion of the eccentric curve of the recess 40 which is actually involved in forming a single eccentric bend in metal tubing is indicated at one end approximately by the numeral 41 and at the other end approximately by the numeral 42, the extent being such as to cover about 90 degrees or the predetermined arc of movement of the tube carrier.

The under side of the forming head 39 is provided with a rigidly mounted cam member 43, the profile of which, at its inner curvature, should substantially correspond with the eccentric curvature of the bottom of the tube recess 40 from 41 to 42, as shown more clearly in Fig. 4 to which reference may also be had. The cam member 43 is secured to the under side of the forming head 39 by means of set-screws 44.

Mounted to slide on the table or platform 21 is a slide 45 which is adapted to be moved in a direction radial of the axis of the carrier spindle 22, and to that end said slide 45 is 5 guided in ways 46 fixed to the table 21. The inner end of the slide 45 is provided with a fixed stud which extends upwardly towards the forming head 39, there being journalled on it an anti-friction roller 48 which is always 10 in contact with the profiled inner face of the cam 43, so that when the forming head moves through its predetermined range of oscillation, the profiled inner face of the cam 43 will cause a movement of the slide 45 which is controlled by the cam. 15

A carriage 49 having a limited travel has a dove-tail sliding connection with the guides 46, as shown more clearly in Fig. 14. The outer end of the aforesaid slide 46 carries a 20 post 50, which is received in a slot 51 of the carriage which extends parallel with the slide 46. Said post 50 is provided with a flange 52 to bear on the bottom of the carriage 49 at both sides of the slot 51. The other end of 25 the post 50 is reduced and screw-threaded and receives a washer 53 and a screw-threaded nut 54 which is adapted to so secure the washer 53 that it, with the flange 52, is adapted to be bound together against the upper and lower 30 surfaces of the carriage, at both sides of the slot 51. In other words, by means of the pin and slot connection as it were, furnished by the post 50 and the slot 51, the carriage is adapted to be adjusted and set in a definite relation with respect to the slide 46, and the 35 setting of the parts after adjustment is more definitely determined and obtained by means of a screw-threaded adjusting spindle 55 which is provided at its outer end with a 40 wrench-head adapting it to be turned. To obtain the desired adjustment of the carriage, the nut 54 is released so that the adjusting spindle 55 may be operated to adjust the carriage, and the desired position of the carriage 45 relative to the slide 45 having been obtained, the nut 54 is again tightened.

Carriage 49 is provided with a pair of jaws, or jaw-like projections 56 in which turn anti-friction rollers 57 which are located at the opposite side of the gap, from the forming head 39, into which certain parts to be hereinafter described are introduced with a view to forming the bend in the tubing. The jaws 56 are connected by a member 58, located inwardly of but parallel with a flange or wedge 59 of the carriage 49, such flange extending at right-angles to the line of movement of the carriage and the slide 45. The connecting member 58 and the jaws 56 with their rollers 57 are mounted on the carriage for movement with respect to the flange or wedge 59. To this end, screw-threaded headed pins 60 extend through the flange 59 and the jaw connecting member 58, the unheaded ends of said pins being provided with nuts 62 screwed

thereunto, while helical expansion springs 61 are coiled about said pins at their heads in such way as to tend to resiliently move the rollers 57 and jaws 56 towards the flange 59 of the carriage. These springs 61 may be 70 manually placed under greater tension through the medium of substantially half-round stepping cams 63 in the form of posts and which are mounted in curved recesses 64 in both ends of the carriage 49, said cams 63 75 being operable through the medium of hand cranks 65. In Fig. 1 the hand cranks 65 are shown as extending in opposite directions in which case the springs 61 move the jaws 56 up to the carriage. In Fig. 2 the hand cranks 80 are shown in broken lines each having been moved through an angle of 90 degrees so as to press the jaws 56 away from the carriage, thus compressing the springs 61.

In Figs. 1 to 4, inclusive, there is shown a 85 forming member 66 and which consists of a straight bar of metal provided with a rigid handle 67. This metallic forming member 66 is preferably a floating one, that is to say, 90 it may be moved by an attendant of the machine when he grasps the handle 67, whereby he may slide the forming member 66 in one direction or the other. The forming member or bar 66 is supported on an accessory table or platform 68, preferably in the form of an 95 elongated bench, the upper surface of which may be lubricated with graphite or the like, so as to permit an easier movement of the forming member. When the machine is to make a bend in metal tubing, this forming member or bar 66 is slid by an attendant into the gap between the forming head 39 and the carrier jaws 56, as more specifically explained 100 hereinafter.

Referring more particularly to Figs. 1, 7 105 and 11, a clamping member 69 is provided consisting of a suitably shaped metallic block, which constitutes one of the members of a vise. The clamping member 69 is provided with a handle 70 and a dowel pin 71 projecting 110 from one end of the inwardly grooved or concave face 72 of the said member, which also has a straight face 73. This clamping member or block 69 has three edges, the two edges which form the faces 72, 73 tapering 115 from the larger end of the member so as to substantially meet at the smaller end of the member. The curve 72 of the member 69 is such as to constitute substantially a continuation of the curve of the bottom of the recess 40 in the forming head 39, when the clamping member 69 is inserted in the outer end of the said recess with its pin 71 seated in a corresponding socket in the forming head, 120 as shown in Fig. 7. This positioning of the clamping member 69 places its straight edge 73 tangential to the curve of the bottom of the recess 40 and provides a straight extension 125 from said recess, for the purpose to be hereinafter explained. 130

Another member of the vise of which member 69 constitutes one of the jaws, consists in a clamping member 74, shown in Fig. 10 having the handle 75 and which has a longitudinal recess 76, with a straight bottom, in that face or edge which is to oppose the straight edge 73 of the clamping member 69. At one side of the recess 76 there extends from one wall of the recess in a plane at right-angles to the plane of the recess, a flange 77. The clamping member 74 is provided at that side opposite to the handle 75 with a pin 78, later on again referred to. The described clamping members 69 and 74 are adapted to 15 clamp a straight portion of the metallic tubing.

Referring more particularly to Fig. 9, the vise of which clamping members 69 and 74 are adapted to form parts, is provided with 20 a base-plate 79 which may be rigidly or removably secured to the forming head 39 by means of fastenings 80. The base-plate 79 is thickened at one end and provided with a shoulder 81 which is adapted to abut against 25 one end of the forming head 39, so that in connection with the fastenings 80 the base-plate of the vise is firmly secured in position at that end of the forming head which constitutes the advancing end of the head. The 30 base-plate 79 is provided with a groove 82 which constitutes an extension of the curved receiving recess of the forming head of the base-plate 79 (see Fig. 7).

It will be seen that when the vise referred 35 to is equipped with clamping members 69 and 74, as shown in Fig. 1, the straight outer end of the metallic tube may be clamped so that it will extend tangentially with respect to the curved bottom of the recess 40, from approximately the point 42.

A swinging arm 83 is pivoted at one end to the base 79 of the vise and is provided at its free end with a threaded eye 84 which receives a screw spindle 85 provided with a 45 handle 86 at its outer end and a pressure head 87 at its inner end. This swinging arm 83 is in outwardly swung position in Fig. 1, but in Fig. 2 it has been shown in operative position.

50 As shown in Fig. 7, the base-plate 79 of the vise is provided with a slot 88 for receiving the pin 78 on the clamping member 74 of the vise. Auxiliary vise means are illustrated comprising a manually operable handle 89 fulcrumed on a pivot stud 90 rigid with the base-plate 79, and at the opposite side of the stud 90 from the handle 89, the hub or head of the handle is provided with a knuckle 91 having a curved engaging edge for setting 55 in a correspondingly curved recess in a chock 92, comprising a body 93 and an angle-member 94. Angle-member 94 is adjustable through the medium of adjusting screws 95 which pass through one flange of the angle-member and the body 93, the adjustment be-

ing held by means of thrust screws 96 which are located under the other flange of the angle-member and are screwed into the body 93. It will here be noted that when the vise-arm 83 is locked in position and the handle 75 member 89 operated so as to throw the chock 92 from the position shown in Fig. 1 to that shown in Fig. 2, that the metal tube is held fast. It may here be stated that Fig. 1 shows the parts of the machine in position with the 75 tube placed so that when the machine is set to hold the tube, the forming head may be turned so as to produce the first bend in the tubing. The drawings therefore do not show a straight tube which has not been bent 80 clamped in position for the first bending operation, nor the position of the forming head when the first bend is produced; except that Figs. 2 and 3 show the machine adjusted and adapted to form the second bend, and except for the difference of set-up of the parts, such as forming members and the like, these Figs. 2 and 3 show all that is necessary for a complete understanding of what follows when the mechanism as shown in Fig. 1 is 90 adjusted for holding the tube preliminary to and during the making of the first bend.

Means are preferably provided to enable a metal tube to be inserted readily in the recess 40 of the forming head 39 and to be removed 95 as readily after a bend has been made. To that end means may be provided, such as shown in Figs. 1, 5 and 15, wherein a clearance member or flange 97 is provided upon the forming head 39 to constitute the outer 100 side wall of the eccentrically curved recess 40. This clearance member 97 may be moved slightly away from the opposite wall of the recess in order to increase the width of the recess for the free entrance of a metal tube, 105 and it may be firmly held when moved in the opposite direction to contract the recess and to cause the opposite surfaces of the recess to firmly engage with the metal tube.

Means for operating the clearance member 97 are preferably, as follows: Forming head 39 is provided with a series of upwardly projecting pivot-studs 98 set back of the working edge of the forming head in substantial parallelism with the curvature of the 115 bottom of the recess 40, and a series of rock-arms 99 are rigidly secured at their inner ends on the studs 98. A series of links 100 pivotally connect the rock-arms 99 with each other, so that a movement of one arm will cause all the other arms to follow. A hand-lever 101 is rigidly secured to one of the pivot-studs 98, which studs are screw-threaded into correspondingly threaded openings in the forming head 39. It will therefore be 120 seen that when the hand-lever 101 is operated so as to move it from the position shown in Fig. 9 to the position shown in Fig. 1, that, with screw threads extending in their proper direction, the pressure on the clearance mem- 130

ber 97 is released, and that when the handle is moved in the opposite direction the clearance member 97 is tightened up. As shown more clearly in Fig. 9, expansion springs 102, 5 coiled within suitable sockets in the forming head 39, are constantly pressing against the clearance member 97 so that when the operating handle is moved from the position shown in Fig. 9 to the position shown in 10 Fig. 1, the springs act automatically to cause an outward movement of the clearance member, and hence the widening of the recess 40 in the forming head 39. A metal tube may then be readily inserted into the recess in the 15 forming head.

Referring to Figs. 4, 5 and 6, mechanism is shown more clearly for operating the clutch 11. This mechanism comprises a slide-rod 103 mounted for a sliding movement in the 20 bearing blocks 16, 16^a and it carries a yoke 104 for operating the friction cone or clutch 11 in the usual manner; that is to say, the yoke has projections taken into an annular groove in the clutch 11, permitting the latter 25 to turn with the drive-shaft 10. The other end of the slide-rod 103 is provided with two separated cams 105, 106 rigidly secured thereon, and a fork 107 is provided with pins 108 which are positioned between the said 30 lars. A hand-lever 109 pivoted at 109^a is provided for the purpose of rocking the fork 107 in one direction or the other, depending upon the direction in which the slide-rod 103 is to be operated, for the purpose of engaging 35 the friction cone or clutch 11 with one or the other of the belt pulleys 12, 13, depending upon the direction in which the mechanism of the machine is to be operated.

The machine is furthermore provided with 40 means for automatically throwing the friction cone or clutch 11 out of engagement with one or the other of the belt pulleys 12, 13, such means comprising a tappet-arm 110 and another tappet-arm 111, the two arms being 45 formed as an angle-member which is secured at its angle-portion upon the spindle 22. For engagement with one or the other of the tappet-arms 110, 111, the slide rod 103 is provided with an abutment pin 112. Briefly, 50 the hand-lever 109 manually controls said automatic throw-out or disconnecting means, while one of the tappet-arms is adapted to come in contact with the abutment 112 when the machine is moving in one direction and 55 the tappet-arm 111 to also come in contact with said abutment when the machine is running in the other direction, each tappet-arm functioning so as to shift the friction cone or clutch 11 and disconnecting it from that belt 60 pulley with which it may be connected.

The mandrel and withdrawal mechanism is 65 more or less common in the art, the mandrel being arranged upon the bench or table 68 in position for use and the feed mechanism being under control of the drive-shaft 10 of the

machine. The metallic mandrel is shown in Fig. 16 and comprises a flexible section or block 113 and a rigid section or shank 113^a which carries the flexibly connected sections 113. The rigid section or shank 113^a is attached to a wire cable or rope 114 which is connected with the more or less well known mechanism which controls the feed of the mandrel, as before mentioned. The described mandrel 113, 113^a is forced into the 70 metal tube 115 which is to be bent by hand, it being customary to smear a suitable lubricant into the flexible portion 113 while the mandrel is resting on the bench or table 68, so as to enable an easier introduction of the 75 mandrel into the tube for the flexible member or section 113 and is of hard metal and has a very tight fit in the tubing. After the metal tubing 115 has been bent, the mechanism connected with the cable 114 automatically 80 pulls the mandrel out of the tubing. It will be noted that the flexible member or section 113 of the mandrel supports the walls of the tubing 115 while it is being bent, the bending taking place between the opposing 85 faces of the forming head of the tube carrier and the forming member 66, which member is carried to the right with reference to Fig. 3 during the act of bending, and when the bend has been completed, the movement of the 90 forming member 66 is arrested by a stop 116 on the forming member 66, which stop then abuts against the adjacent jaw 56 of the carriage or slide 49.

When the bending member 66 is out of use, 95 it is slid out of the machine and along the bench or table 68. In the operation of the machine the attendant grasps the handle 67 and slides the forming member 66 so as to bring its inner end into the gap between the 100 recessed face of the forming head 29 and the rollers 57. In adjusting the machine for producing the first bend 117, indicated in Fig. 2, the bending members of the machine will first be adjusted to the position shown in Fig. 1. 105 The clearance member 97 will be in slightly raised position so as to enable the metallic tube 115 to be readily introduced into the recess 40 of the forming head. The tubing 115 having been thus introduced into the forming 110 recess, the operating handle 101 of the clearance member 97 is moved from the position shown in Fig. 1 to that shown in Fig. 2, thereby sufficiently contracting the width of the 115 recess 40 as to snugly fit on the tubing 115, the flexible mandrel preferably being at the time already introduced into the tubing. Of course it will be understood that in some cases the clearance member 97 and its operating mechanism may be omitted, in which case 120 the forming recess 40 could have three relatively stationary walls, between which the metal tubing 115 may be operated upon. It will be seen that when the metal tube is introduced between the forming head 39 and 125 130

the forming member 66, the tubing will be in contact with the opposing faces of the vise previously described, comprising the clamping members 69 and 74, the clamping member 74 being then loose and unclamped. The attendant of the machine then swings the arm 83 from the position shown in Fig. 1 to that shown in Fig. 2 and turns the handle 86 so as to cause the head 87 of the screw 85 to firmly engage the clamping member 74, shown in Fig. 1, whereby a vise grip is established by the two clamping members 69 and 74 upon the metal tubing 115. The attendant then swings the handle lever 89 from the position shown in Fig. 1 to that shown in Fig. 2, when the clamping member 74 is more rigidly and firmly held than it would be by the mere clamping action of the head 87 of the screw spindle. A firm rigid grip on the metal tubing 115 must be had by the vise, before the machine is caused to operate. The attendant furthermore moves the handles 65 from the positions shown in Fig. 1 to those shown in Fig. 2, thereby compressing the springs 61 and pressing the anti-friction rollers 57 against the forming member or bar 66, thereby establishing a firm contact between the forming bar 66 and the tube, and between the tube and the bottom of the forming recess at 42 (Fig. 1).

The forming elements of the machine having thus been adjusted and set, the machine is in a condition to be operated. The attendant moves the handle 109 so as to bring the cone or clutch 11 into clutching engagement with the belt pulley 12, so that the power transmitting mechanism of the machine will be operated by the drive-shaft 10 and will turn the large gear 25 in the direction of the arrow (Fig. 6), thereby rotating the spindle 22 and the tube carrier through an arc of approximately 90 degrees, and at the completion of this turning movement the tappet 111 is brought into contact with the abutment 112, resulting in disconnecting the clutch 11 from the belt pulley 12 and stopping the machine automatically. It will be understood that when the operating parts appertaining to the bending act, and which are shown in Fig. 1, are adjusted and set as before described, the first bend 117 is made in the tubing 115 when the tube forming head 39 of the tube carrier is oscillated on the axis of the spindle 22 through the aforementioned arc. The eccentric contour of the forming face of the head 39 is such that an eccentric bend 117 (the first bend) is made in the metal tubing, the outer end of this tubing being firmly held in the vise which carries that end through the described arcuate range of movement. The portion of the tubing which is to receive the first bend 117 will be acted upon by that length of the forming face of the head 39 which is located approximately between the points 41 and 42 in Fig. 1, and that

portion of the forming face will roll upon the corresponding length of tubing to be bent and act in the nature of an anvil, around which the bend is formed. Also during the arcuate movement of the forming head, the profile of the cam 43 thereon acts upon the roller 48 so as to move the carriage 49 with the movement in consonance with or corresponding to the extent of departure of the eccentric face of the head 39 from its shortest distance from the axis of the spindle 22 to the longest distance from said axis. In this way the profile of the cam 43 will always cause the anti-friction rollers 57 of the carriage 49 to be kept in contact with the corresponding edge of the forming member or bar 66, thereby offering the proper amount of resistance to any movement of said forming member or bar away from the forming face of the head 39. During this bending movement, the forming member or bar will be caused to move to the right of Fig. 1, until the stop 116 strikes the jaw 56 of the carriage 49, when further movement of the member 66 will be arrested, and the machine will at that time also be brought to a stop by reason of the clutch 11 being automatically disconnected from the belt pulley 12.

When the operation of the machine in forming the first bend 117 is arrested, the forming head 39 is caused to have a reverse movement. The attendant will shift the handle 109 so as to bring the friction cone or clutch 11 into operative engagement with the belt pulley 13, the tappet 110 being then in contact with the abutment 112. This will effectuate a reverse movement of the forming head 39 to bring the forming head, the vise and the forming member 66 back to their original positions, but the mandrel control mechanism will still be in operation, and the mandrel will be forcibly withdrawn from within the bend in the tubing and freed from the tubing until the flexible member thereof rests upon the bench or table 68, when the movement of that mechanism is arrested. The attendant then releases the members of the vise from their hold on the tube and the forming member 66 is also moved further away onto the bench or table 68 so as to draw it out of the gap between the forming head and the carriage 49, the operator first actuating the handle 65 so as to release the forming member 66 from the jaws 56 and their rollers 57. The clearance member 97 is now released from its hold on the metal tubing, by the operation of the handle 101. The metal tubing with the first bend therein can now be readily withdrawn from the machine.

If a second bend is to be made, as would be the case when the tubing is to be bent for the formation of the head and foot portions of bedsteads, clamping members shown in Figs. 12 and 13 are applied to the machine, which conform at their gripping faces with

the contour of the first bend, as they preferably grip the tubing at that bend. In Fig. 2 the substitute clamping members are shown in position for clamping the tubing at the 5 first bend. For enabling the vise to grip the first bend, there are provided a clamping member 118, provided with a dowel pin 119, and a clamping member 120. The clamping member 118 is tapered longitudinally and 10 also curved. Its inward curve is adapted to conform to the curve of the recess 82 in the base of the vise, and its dowel pin 119 fits into the hole at the bottom of said recess. The outward curve of the clamping member 15 118 constitutes a continuation of the bottom of the recess in the forming head 39 and conforms to the eccentric curvature of the inner bend of the tube portion 117. The clamping member 120 is adapted to be arranged 20 in the device for opposing the clamping member 118. It is provided with a handle 121 to enable the convenient handling as it is heavy and is provided with an inwardly curved or concaved face 122. 25 Clamping member 120 is also of tapering form, lengthwise, and the curve 122 is along one side of the taper, while the other side constitutes a straight edge 124. It is furthermore provided with a tapering longitudinal flange 123 extending along one edge of the concave face 122 and with a pin 125 projecting from the bottom of the clamping member. The clamping member 120 is recessed upon the base-member 79 of the vise 30 with its pin 125 entered into the slot 88 of the base of the vise, its inwardly curved face 122 opposing the outward curve of the clamping member 118, its flange 123 being engaged under one side of the bend 117 of the metal 35 tubing. When the clamping members are properly adjusted at opposite sides of the bend 117 the swinging arm 83 is moved over so that the attendant may, by turning its handle, cause the head 87 to firmly bear upon the straight edge 124 of the clamping member 120. Next, the hand lever 87 is operated 40 so as to cause the chock 92 to also firmly bear upon the straight edge 124 of the clamping member 120. Of course the other parts 45 which have to be manipulated in order to enable the introduction of the metal tubing and the adjustment to the working position have to be adjusted and fixed after adjustment as described in connection with the 50 formation of the first bend. The metal tubing will then be firmly gripped in the machine at the first bend 117, as shown in Fig. 2, and the machine is ready to be operated so as to turn the forming head through 55 an angle of approximately 90 degrees about the axis of the spindle 22. The machine is then operated as before described for producing a bend in the metal tubing and when 60 the forming head 39 has arrived at approximately the position shown in Fig. 3, the sec- 65

ond bend 126 will be complete in the metal tubing. The machine is then reversed, as before described, after which the mandrel is removed from the tubing. By some such operations as before described, the desired 70 curvature of the head and foot portions of metallic bedsteads, for example, may be produced in an economical and expeditious manner by the machine of the present invention.

If desired, the forming head 39 may be 75 equipped with an additional vise for gripping the outer straight portion 150 (Fig. 2) of the tubing during the formation of the second bend, and thereby positively preventing deformation of the first bend during the 80 subsequent operation. Furthermore, the cam 43 which controls the carriage 45, may be replaced by any other suitable type of cam which is synchronized in its movements with the forming head, but not necessarily 85 mounted co-axially therewith.

It is obvious that the invention is susceptible of a wide range of modification other than those specifically mentioned and still be within the spirit and scope of the ap- 90 pended claims.

Having thus described my invention, what I claim is:

1. In a tube bending machine, the combination of a pair of opposed forming members, 95 one of which has a profile the same as the desired bend, means for holding a tube to be bent, between the opposed forming members and in fixed relation to the profiled member, and means for imparting a tangential move- 100 ment and also a lateral movement to one of the forming members relatively to the other forming member during the bending operation.

2. In a tube bending machine, the combination of a pair of opposed forming members, 105 one of which has an eccentrically curved profile corresponding to the desired bend, means for holding a tube to be bent, between the opposed forming members and in fixed relation 110 to the profiled member, means for imparting a tangential movement to the other forming member relatively to the said profiled forming member, and means for moving said other forming member laterally during said tan- 115 gential movement.

3. In a tube bending machine, the combination of a pair of opposed forming members, 120 one of which has an eccentrically curved profile corresponding to the desired bend, means for holding a tube to be bent, between the opposed forming members and in fixed relation to the profiled member, means for turning the profiled member about a fixed axis, and a cam operable with said profiled member for 125 moving the other forming member laterally during said turning movement.

4. In a tube bending machine, the combination of a pair of opposed forming members, 130 one of which has a curved profile correspond-

ing to the desired bend, and the other being substantially straight and free to move longitudinally, tube gripping means fixed to said profiled forming member and adapted to hold 5 a tube to be operated upon, between the opposed forming members, means for imparting arcuate motion to the profiled forming member and tube gripping means to bend a tube held therein, and means to laterally move 10 the longitudinally movable forming member to correspond with the curve of the profiled forming member.

5. In a tube bending machine, the combination of a pair of opposed forming members, 15 one of which has an eccentrically curved profile corresponding to the desired bend, and the other being free to move longitudinally, tube gripping means fixed to said profiled forming member and adapted to hold a tube to be operated upon, between and in engagement 20 with said curved profile and a side of the longitudinally movable forming member, means to rotate the profiled forming member and tube gripping means through the arc of a 25 circle, and exerting a rolling pressure on the tube, and means for moving said longitudinally movable forming member laterally to compensate for the eccentricity of the bend.

6. In a tube bending machine, the combination of a rotatable forming head having a curved profile, a straight forming bar opposed to the curved profile of said forming head and spaced from said curved profile a 30 distance equal to the width of a tube to be operated upon, a cam rotatable with the forming head, a carriage for acting upon the straight forming bar and controlled by the cam, tube gripping means carried by the forming head, and means for rotating the forming head through the arc of a circle 35 whereby to bend a tube to the curved profile of said forming head.

7. In a tube bending machine, the combination of a rotatable forming head having a curved profile, a straight forming bar opposed to the curved profile of said forming head and spaced from said curved profile a 40 distance equal to the width of tube to be operated upon, a cam rotatable with the forming head, a carriage for acting upon the straight forming bar and controlled by the cam, tube gripping means carried by the forming head, and means for rotating the forming head through the arc of a circle, the straight forming bar being free to move longitudinally 45 whereby to exert a rolling pressure on a tube to bend it to the curved profile of said forming head.

8. In a tube bending machine, a forming head having a grooved edge for reception of a tube to be bent, the bottom of the groove being curved to correspond with the desired bend, a forming bar opposed to said grooved edge for confining a tube in the groove, said

forming bar being freely slidable tangentially with respect to the grooved edge of the forming head, tube clamping means mounted for movement with the forming head, means for rotating the forming head and tube clamping means through an arc of a circle, 70 and means for automatically arresting the movement of said parts at a predetermined limit.

9. In a tube bending machine, a forming head having a profiled edge corresponding to the bend to be produced, a longitudinally movable forming member opposed to said profiled edge for forcing a tube against the same, tube clamping means mounted for movement with the forming head, means for 75 rotating the forming head and tube clamping means through an arc of a circle, and means for automatically arresting movement of said parts, including the longitudinally movable forming member, at a predetermined 80 limit of movement.

10. In a tube bending machine, a forming head having a grooved edge for reception of a tube to be bent, the bottom of the groove being curved to correspond with the desired bend, a forming bar opposed to said grooved edge for confining a tube in the groove, said forming bar being freely slidable tangentially with respect to the grooved edge of the forming head, tube clamping means mounted for movement with the forming head, means for rotating the forming head and tube clamping means through an 90 arc of a circle, means for simultaneously moving the forming bar laterally with respect to the axis of the forming head, and means for automatically arresting movement of said parts at a predetermined 95 limit of movement.

11. In a tube bending machine, a forming head having a profiled edge corresponding to the bend to be produced, a forming bar opposed to said profiled edge for pressing a tube against the same, tube clamping means mounted for movement with the forming head, means for rotating the forming head and tube clamping means through an arc of a circle, and means for arresting and reversing the movement of said parts to return them to their original positions after the desired 100 bend has been produced.

12. In a tube bending machine, a forming head having a grooved edge for reception of a tube to be bent, the bottom of the groove being curved to correspond with the desired bend, a forming bar opposed to said grooved edge for confining a tube in the groove, said forming bar being freely slidable tangentially with respect to the grooved edge of the forming head, tube clamping means mounted for movement with the forming head, means for rotating the forming head and tube clamping means through an arc of a circle, and means for arresting and reversing the 110 120 125

movement of said parts to return them to their original positions after the desired bend has been produced in the tube.

13. In a tube bending machine, a forming head having a profiled edge corresponding to the bend to be produced, a forming bar opposed to said profiled edge for pressing a tube against the same, tube clamping means mounted for movement with the forming head, means for rotating the forming head and tube clamping means through an arc of a circle, a carriage for maintaining the forming bar in opposition to the forming head, means for moving the carriage laterally with respect to the axis of the forming head while the latter is rotating, and means for arresting and reversing the movement of said parts to return them to their original positions after the desired bend has been produced in the tube.

14. In a tube bending machine, a forming head having a grooved edge for reception of a tube to be bent, the bottom of the groove being curved to correspond with the desired bend, a forming bar opposed to said grooved edge for confining a tube in the groove, said forming bar being freely slideable tangentially with respect to the grooved edge of the forming head, tube clamping means mounted for movement with the forming head, means for rotating the forming head and tube clamping means through an arc of a circle, a carriage for maintaining the forming bar in opposition to the forming head, means including a cam for moving the carriage laterally with respect to the axis of the forming head while the latter is rotating, and automatic means for arresting and manual means for reversing the movement of said parts to return them to their original position after the desired bend has been produced in the tube.

15. In a tube bending machine the combination of a forming head having an eccentrically curved profile corresponding to that of the desired bend, a freely movable forming member opposed to the curved profile of said forming head and adapted to engage the opposite side of a tube to be bent against said curved profile, a carriage for imparting slightly yielding pressure to said freely movable forming member, means for oscillating the forming head about a fixed axis, a cam rotatable with the forming head and provided with a profile corresponding to that of the forming head, and means on the carriage for engaging said cam whereby to move said carriage and freely movable forming member laterally with respect to said fixed axis of oscillation.

16. In a tube bending machine the combination of a forming head having an eccentrically curved profile corresponding to that of the desired bend, a freely slideable forming bar opposed to the curved profile of said

forming head, means for oscillating the forming head about a fixed axis, a carriage movable toward and away from said fixed axis, pressure rollers mounted on the carriage and adapted to engage the forming bar to force it toward the forming head, means for withdrawing said rollers from engagement with the forming bar, means for moving the carriage simultaneously with the forming head to compensate for eccentricity of the bend, and means for automatically arresting the movement of said parts at a predetermined limit.

17. In a tube bending machine, the combination with a movable forming member, of a tube clamping vise mounted upon said forming member, said vise adapted to include a plurality of sets of vise jaws selectively interchangeable for gripping either an unbent tube or one which has been partly bent to form a bed-end or the like, and an arm mounted swingably upon the forming member for movement away from the jaws and having at its outer end means for clamping the jaws upon the tube.

18. A forming head for a tube bending machine comprising a body member having a curved edge profile corresponding with the desired bend, and flanges extending beyond said curved edge and forming therewith a groove for the reception of a tube to be bent, said flanges restraining the sides of a tube from bulging during the bending operation, one of said flanges being movable toward and away from the other flange, a plurality of actuating members for said movable flange, and means for simultaneously operating said actuating members.

19. A forming head for a tube bending machine comprising a body member having a curved edge profile corresponding with the desired bend, and flanges extending beyond said curved edge and forming therewith a groove for the reception of a tube to be bent, said flanges restraining the sides of a tube from bulging during the bending operation, one of said flanges being movable toward and away from the other flange and being provided with a plurality of apertures, clamping posts extending through said apertures and in threaded engagement with the body member of the device, rock-arms carried by the posts above the movable flange, links connecting the extremities of the adjacent rock-arms, and a hand lever connected to one of the rock-arms, movement of which is communicated to all the clamping posts through said links.

20. In a tube bending machine, the combination of a forming member having an eccentrically curved profile, a laterally movable, opposing forming member, means for holding a tube to be bent between the forming members, means for moving the eccentrically curved forming member, and means positively actuated by the first mentioned forming member

to laterally move the opposing forming member correspondingly with the change of profile of the eccentrically curved forming member.

5 21. In a tube bending machine, the combination of a forming member having an eccentrically curved profile, a laterally movable, opposing forming member, means for hold-

ing a tube to be bent between the forming members, means for moving the eccentrically curved forming member about an axis of rotation, and a cam to laterally move the opposing forming member correspondingly with the change of profile of the eccentrically curved forming member.

LOUIS FRANK.
